UNITED STATES PATENT OFFICE

136,367

DESIGN FOR A BUBBLE PIPE OR THE LIKE ARTICLE

Paul Lazarus, Brooklyn, N. Y., assignor to Peerless Products Company, Brooklyn, N. Y., a partnership, composed of Paul Lazarus and Louis M. Lazarus

Application June 22, 1943, Serial No. 110,504

Term of patent 14 years

To all whom it may concern:

Be it known that Paul Lazarus, citizen of the United States and resident of Brooklyn, New York, in the county of Kings and State of New York, has invented a new, original, and ornamental Design for a Bubble Pipe or the Like Article, of which the following is a specification, reference being had to the accompanying drawing,

forming part thereof, in which, Fig. 1 is a side elevational view of a bubble pipe showing my new design. Figs. 2, 3 and 4 are top plan, bottom plan and end views, respectively, thereof.

I claim:

The ornamental design for a bubble pipe or the like article, as shown.

PAUL LAZARUS.
